(57) **CLAIM**

An ornamental design for a ball mount for an accessory device, as shown and described.

DESCRIPTION

FIG. 1 is a perspective view of a ball mount for an accessory device, in accordance with an embodiment;

FIG. 2 is a side view of a ball mount for an accessory device, wherein each side view is the same, in accordance with an embodiment;

FIG. 3 is a top view of the ball mount for an accessory device, in accordance with an embodiment; and,

FIG. 4 is a bottom perspective view of the ball mount for an accessory device, in accordance with an embodiment.

In the drawings, thin and/or broken lines illustrate contours and/or component interfaces which form no part of the claimed design.

1 Claim, 4 Drawing Sheets
